APPARATUS FOR REMOVING WOOD WASTE

Charles V. Anderson, Seattle, Wash., assignor to
 Anderson Blow-Pipe and Manufacturing Company, a corporation of Washington

Application November 21, 1949, Serial No. 128,660

3 Claims. (Cl. 302—37)

1

This invention relates to devices for increasing and regulating degrees of suction, and particularly suction for removing waste matter from wood working machines.

In manufacturing and finishing lumber and wood products, a relatively large amount of saw dust, shavings, and other particles forming waste matter are released and which must be constantly removed. The removal is most economically accomplished by relatively large tubes into which the waste matter is drawn by air suction and thence carried away and discharged. Such suction is preferably supplied by relatively large fans connected to the tubes at a suitable distance back from the mouths, or receiving ends thereof, and driven by ordinary electric motors adapted for rotating the fans at uniform speeds to remove the normal amounts of waste as formed.

In practice however the amounts of waste being formed frequently vary and when more than normal amounts enter the tubes their passage is slowed up or retarded and the waste accumulates or clogs the tubes, and it is necessary to increase the suction to meet the increased load. It is therefore an object of this invention to provide means for increasing the suction through the tube for drawing in and driving away all and increased amounts of waste without changing the speed of the fan.

A particular object is to provide means for releasing a portion of the air pressure from behind the fan to prevent back pressure in the tube, and thereby to increase the suction effects in front of the fan for drawing in and driving away all waste material formed.

A further particular object is to provide a doorway or outlet in the top of the chamber behind the fan for diverting such portions of the air as may exert a back pressure in the tube and to provide a plurality of relatively short baffle plates or dampers pivotally mounted across the doorway for closing the same for normal loads of waste, together with a lever pivotally connected with the dampers for elevating the plates for increasing the suction for greater loads, and for retaining the dampers in opened and closed positions alternately.

With these and other objects to be herein-after stated, I have illustratively exemplified my invention by the accompanying drawings, of which:

Figure 1 is a side elevation, with parts broken away, and showing the dampers in open positions. Figure 2 is a top plan taken on line 2—2 of Fig. 1,

2

but showing the dampers in closed positions. Figure 3 is an enlarged fragmentary detail view of the rear side of the chamber behind the fan, showing the dampers in closed positions, together with means for turning the dampers, and Figure 4 is an enlarged fragmentary detail view taken on line 4—4 of Fig. 3, showing connections of lever for operating the dampers.

Like characters on the different figures represent like parts. Numeral 5 represents a housing, in which is mounted a fan 6 on a shaft 7. The shaft and fan are rotated clockwise by a conventional electric motor 8, to provide uniform air power. The blades 9 of the fan may be connected by a band 10 along the outer portions thereof for rigidity. Attached to one side of the housing is a tube 11 which is extended forwardly to any point required for receiving and gathering wood waste of various weights such as saw dust, shavings, etc., to be drawn into the housing by suction created by the fan. Extended rearwardly from the housing is a chamber A, having side walls 12 and 12' attached by flanges 13 to the housing. A discharge pipe 14 of suitable dimensions is connected to the rear end of the chamber as by flanges 15 and extended to any desired location for discharge of the waste by air pressure from behind the fan.

When the supply of waste is normal the suction in the tube and pressure in the chamber and pipe from the uniform velocity of the fan is adapted to carry the waste as fast as the same is collected in the mouth of the tube; but when the amount of waste is increased above normal, it becomes necessary to increase the suction in the tube to overcome the weight of the loads in the tube and back pressure from the loads in the chamber and discharge pipe. To provide such increased suction in front without increasing the velocity of the fan, it is necessary to decrease the back pressure behind the fan, and I accomplish this by application of any number of damper plates pivotally mounted across the otherwise open area or doorway over the upper portion of the chamber. Said plates to be regulated by a hand lever 16, and bar 17, connected together by pivot pin 18.

The damper plates are indicated by the letters a, b, c, d, and e, and are connected operatively to the bar by links f, g, h, and i and pivots p, and by the upper end of the lever n. The damper plates are supported by attachment to rods j, k, l, m, and 19, all of which rods are extended across the doorway horizontally and pivotally through the side walls 12 and 12' and outside bearing

bosses *o*. It will be understood that the rod *19* is attached to the upper end *n* of the lever for shifting the positions of the damper plate *c*.

The dampers are preferably extended laterally from the links on obtuse angles thereto and are of suitable width combined to substantially enclose the doorway when disposed horizontally as seen in Figs. 2 and 3, when the lever is drawn diagonally below the bar, for use under normal loads of waste. But when it becomes necessary to divert a portion of the air from the chamber in front of the pipe to decrease the back pressure and for increasing the suction in the tube, the lever is shifted to vertical position as shown in dotted lines Fig. 3, whereby the damper plates are inclined obliquely to provide open spaces between them to compel escape of the back pressure as indicated by the positions shown in Fig. 2. As the damper plates are preferably supported on a plane above the top of the discharge pipe, the heaviest portions of the waste and most of the lighter portions follow a level line of travel from the base of the housing into the pipe, but any of the lighter portions which escape between the dampers may be carried away by any discharge outlet as *20*.

In order to guide and retain the lever in any desired position, for maintaining the damper plates in suitable positions, a bracket *21* is extended from the wall *12* on which is supported a quadrant *22*, provided with a slot *23*, in which a bolt *24* is slidably disposed and thence through the lever, and may be latched in any desired angle by a nut *25*. By experiments and practice, I have discovered that a single damper used alone would have to be so wide that it would project down into the waste in lower portion of the chamber, but a plurality of relatively narrow plates having their fronts tipped downward diagonally will scoop up and divert sufficient of the upper portions of the currents, without retarding the waste or diverting the latter from travel into and from the pipe.

Having described my invention, I claim as new for Letters Patent:

1. An apparatus for removing wood waste, comprising, a chamber horizontally disposed and discharge pipe from one end thereof for passage of wood waste therethrough under air pressure being provided with a doorway across the top portion thereof above the level of the top of the pipe for the escape of portions of the air above the waste, means for normally closing the doorway, and for regulating the escape of the air including a plurality of relatively short damper plates mounted on pivots across the doorway, links affixed to one of the ends of the pivots and ex-

tended laterally therefrom for alternately closing the doorway and opening the same for diverting air from top of the chamber and for regulating the flow of waste through the lower portion of the chamber, a bar horizontally disposed and pivotally connected to the outer ends of the links for turning a plurality of the damper plates simultaneously, and a lever pivotally connected with the bar for moving the same to and fro for opening and closing the damper plates and for retaining the plates in such opened and closed position respectively.

2. In an apparatus for regulating pressure in a horizontally disposed chamber and discharge pipe, said chamber being normally open across its upper part for a doorway, a plurality of relatively short damper plates pivotally mounted from their rear edges across said doorway for normally closing the doorway, a lever operatively connected with the damper plates for turning the same diagonally into spaced relation from each other to provide scoops to divert a portion of the air in the chamber and to increase the flow of the waste through the lower portion of the chamber into the pipe, and to prevent back pressure from the chamber against flow of waste into the same.

3. An apparatus for removing wood waste under air pressure, including a chamber and pipe horizontally disposed for discharging the waste therethrough, in combination with means for varying the pressure, the said chamber having a doorway over the top thereof, rods pivotally disposed through the sides of the chamber and extended across the doorway, a plurality of relatively short damper plates attached to the fronts of the rods for closing the doorway, a connecting bar horizontally disposed on one side of the chamber, links attached to one of the ends of the rods and pivotally connected with the bar, for opening and closing the damper plates over the doorway for varying pressure in the chamber and pipe, and a lever for shifting the bar to and fro for actuating the links and turning the fronts of the dampers diagonally for scoops for skimming portions of the air from the top portion of the chamber above the flow of waste beneath.
